ATTORNEYS

UNITED STATES PATENT OFFICE.

JOHN A. LANDAN, OF NEW YORK, N. Y.

GARMENT HANGER.

Substitute for application Serial No. 442,643, filed February 5, 1921. This application filed October 10, 1921. Serial No. 506,611.

To all whom it may concern:

Be it known that I, JOHN A. LANDAN, citizen of Russia, residing at 1547 Minford Place, Bronx, in the county of Bronx, city 5 and State of New York, have invented certain new and useful Improvements in Garment Hangers, of which the following is a specification.

My invention relates to a new and improved construction of hanger and a method 10 of making the same.

One of the objects of my invention is to provide a coat hanger which may be readily secured to a wall or the like.

15 Another object of my invention is to provide a coat hanger having a projecting nail part, which will be protected by the hanger projection when said hanger is being transported.

20 Another object of my invention is to provide a coat hanger, or the like, which can be readily and cheaply manufactured.

Fig. 1 is a side view of the assembled coat hanger.

25 Fig. 2 is a front view.

Fig. 3 shows the same parts as Fig. 1, but in a different relative position.

Fig. 4 is a section along the line 4—4 of Fig. 1.

30 Fig. 5 shows the two parts of the said coat hanger about to be assembled.

Fig. 6 is a front view of Fig. 5.

Fig. 7 is a section along the line 7—7 of Fig. 6.

35 My improved coat hanger is preferably made of two parts, each of which is formed of resilient, bendable metal that can be preferably shaped or stamped by means of dies.

The holding, or body portion 1, is provided with a centrally perforated arch 2, a hook portion 3, and a nail portion 4. The nail portion 4, has a generally triangular contour, as shown in Fig. 4 and its edges are serrated so as to produce a series of 40 ratchet teeth, which are inclined towards the side body portion. As can be readily seen in Fig. 2, the nail portion 4, is stamped out from the body portion 1. By means of these serrations, the nail portion 4, can be very

45 firmly secured to the wall or the like, because these serrations, or teeth, prevent the said nail portion 4 from being withdrawn.

The hanger portion 5 is initially shaped by a die so as to be laterally curved or bent, 50 as clearly shown in Fig. 6. Because of this

contour, the enlarged point 6 can be readily inserted through the opening 7, of the central arch portion 2, until the said enlarged point 6 has passed within the said arch portion, as clearly shown on Fig. 1. 60

When the said hanger projection 5 is now straightened out so that the entire body thereof is parallel to a plane passing through the vertical axis of the body portion 1, then the hanger projection 5 can no 65 longer be withdrawn from the body portion 1, because the head 8 abuts against the body portion 1, when the said hanger portion 5 is moved upwardly. This is shown in Fig. 3.

The hanger portion 5 can be lengthened 70 that the point 8 can be snapped over the top of the body portion 1, when the said hanger projection 5 will protect or guard the nail portion 4. In this position the head 8 prevents the hanger portion 5 from being 75 withdrawn from the body portion 1.

The body portion 1, can be provided with a hole 10, through which a nail can be driven if desired.

This application is a continuation of and 80 a substitute for my application Serial Number 442,643, filed February 5, 1921, in the United States Patent Office, for a garment hanger.

It is obvious that the entire device can 85 be made of two pieces of metal, suitably stamped into shape by means of dies, and that it can be very readily and efficiently assembled or taken apart.

I have shown a preferred embodiment of 90 my invention but I do not wish to be limited to the details thereof, as numerous changes and omissions can be made without departing from its spirit.

What I claim is:

1. A method of making a garment hanger or the like, which consists in making a body portion provided with a slit and in forming a hanger portion having an enlarged point adapted to pass through the said slit only 100 when the said hanger portion is laterally bent with respect to the said body portion, the said hanger portion being formed in such laterally bent condition, inserting the point of the said hanger portion through the said slit so as to connect the said body portion and the said hanger portion, and then straightening the said hanger portion so as 105 to prevent the removal thereof from the body portion. 110

2. In the art of making a garment hanger or the like, having a body portion with a slit, and having a hanger portion provided with an enlarged point, those steps in the 5 art which consist in laterally bending the said hanger portion so that the said enlarged point can be passed through the said slit and then straightening the said hanger portion so that its enlarged point can no longer 10 be withdrawn from the said slit.

3. A garment hanger or the like having a body member provided with a slit intermediate the ends thereof, and a hanger portion made of bendable material and provided 15 with an enlarged point and projecting through the said slit and with an enlarged head adapted to abut against the body member and to prevent the said enlarged point from being withdrawn from the said slit, 20 the said hanger member being so dimensioned that the said enlarged point can be withdrawn from the said slit only if the said

head portion is bent over to one side of the said body member.

4. A garment hanger or the like having a 25 body member provided with a slit intermediate the ends thereof, and a hanger portion made of bendable material and provided with an enlarged point and projecting through the said slit and with an enlarged 30 head adapted to abut against the body member and to prevent the said enlarged point from being withdrawn from the said slit, the said hanger member being so dimensioned that the said enlarged point can be 35 withdrawn from the said slit only if the said head portion is bent over to one side of the said body member, the side body member having a nail portion provided with ratchet-like serrations.

In testimony whereof I hereunto affix my signature.

JOHN A. LANDAN.
